UNITED STATES PATENT OFFICE

JOSEPH WILHELM MELLWIG, OF ZURICH, SWITZERLAND

MACHINE FOR SCRAPING THE FLOOR

Application filed November 2, 1929, Serial No. 404,224, and in Switzerland November 9, 1928.

My invention relates to improvements in floor scraping machines and the like.

The object of the invention is to provide one or a plurality of layers of steel chips on a roller and securely uniting the chips within a layer and the layers to one another.

This and other like objects are attained by the novel construction and combination of parts hereinafter described and shown in the accompanying drawing, in which

Fig. 1 is a vertical cross-section of a roller constructed in accordance with the present invention;

Fig. 2 is a longitudinal cross-section of the roller; and

Fig. 3 illustrates in an enlarged view the details of the stitching by means of which the steel chips and steel chip layers are held together.

20 The device is mounted on a rotatable shaft 1 carrying a hollow shaft 2. The hollow shaft 2 carries sleeves 3 and 4 adapted to slide with respect to the hollow shaft 2.

25 Arms 5 are pivotally mounted in ears 6 projecting from the sleeves 3 and 4. The cylindrical wall of the roller is constituted by sectors 7 from which project ears 8 in which the outer ends of arms 5 are pivotally mounted.

30 Adjacent ends of sectors 7 have undercut overlapping edges as indicated at 9. A hand wheel 10 formed with an internal thread is screwed on a threaded portion 11 of the hollow shaft 2, the boss of the hand wheel contacting with the sleeve 4. The sleeve 4 may thus be moved to the left (Fig.

35 2) by turning the hand wheel 10, causing thereby through the agency of the arms 5, the sectors 7 to be moved outward, thus increasing the outer diameter of the roller.

40 A series of pins 12 projects from the outer wall of each sector 7 to hold in place a cloth of wire, linen or other suitable fabric cover 13. 14, 15 and 16 are three layers of steel chips. The innermost layer 14 is sewed on

45 the cloth covering 13 by means of a wire 17, and to the adjacent layer of steel chips 15 by means of a wire 18, the wire 18 passing through slip knots formed by the wire 17. The third outermost layer 16 is secured to

50 the layer 15 by means of a sewing wire 19

which passes through slip knots formed by the wire 18. The wires 17, 18 and 19 are preferably of angular cross section and they pass back and forth through the bodies of the masses 14, 15 and 16 securely to unite them.

If the covering is damaged, only the outermost layer 16 of steel chips will be released from the roller and the scraping of the floor may be continued with the adjacent layer 15.

If it is desired to detach the cloth covering 13 and the layers 14 to 16 from the roller, this can be readily done by turning the hand wheel 10 to the left and thus reducing the outer diameter of the roller.

I claim:—

1. A scraping unit for floor scrapers, comprising a supporting member, a fabric covering therefor, means for retaining the fabric covering against sliding on the supporting member, a layer of steel chips engaging said fabric covering, and strand material for maintaining said steel chips in layer form and for securing said layer to the fabric covering.

2. A scraping unit for floor scrapers, comprising a tubular supporting member, means for varying the diameter of said member, a fabric covering for said supporting member, pins for retaining said fabric covering in position on said supporting member, a layer of steel chips engaging said fabric covering, and strand material for maintaining said steel chips in layer form and for securing said layer to the fabric covering.

3. A scraping unit for floor scrapers, comprising a tubular supporting member including sectors having overlapping edges, a fabric covering for said supporting member, means for retaining the fabric covering in position on said supporting member, a layer of steel chips engaging said fabric covering, and strand material for maintaining said steel chips in layer form and for securing said layer to the fabric covering.

4. A scraping unit for floor scrapers, including a layer of steel chips, said layer comprising a mass of superimposed steel chips and a wire angular in cross section passing back and forth through the body

of said mass whereby the latter is securely united.

5. A scraping unit for floor scrapers, including a series of overlying layers of steel chips, each layer comprising a mass of superimposed steel chips and strand material passing back and forth through each layer, the strand material of one layer passing through loops in the strand material of an adjacent layer to secure the several layers together.

In testimony whereof I have signed my name to this specification.

JOSEPH WILHELM MELLWIG.
